UNITED STATES PATENT OFFICE.

OTTO WILLIAM MEISSNER, OF MONTREAL, QUEBEC, CANADA.

TRACK-SANDER.

1,202,871.

Specification of Letters Patent.

Patented Oct. 31, 1916.

Application filed June 26, 1915. Serial No. 36,596.

To all whom it may concern:

Be it known that I, OTTO WILLIAM MEISSNER, a citizen of the United States, and resident of the city of Montreal, Province of Quebec, Canada, have invented certain new and useful Improvements in Track-Sanders; and I do hereby declare that the following is a full, clear, and exact description of same.

10 This invention relates to track sanders for use with electric cars or steam railway cars and appertains particularly to devices wherein the sand is discharged upon the track by air or other pressure.

15 A difficulty experienced with track sanders of the identified type as heretofore constructed has been the frequent clogging of the sand delivery pipe from the sand box to the track, such clogging being due to the fact that a residue of the sand from the box remains in the delivery pipe after the application of the device by the operator, the residue being such as to form a sand plug which retards subsequent discharges and 25 this retardation, even if but momentary, is likely to have serious consequences.

An object of this invention, therefore, is to prevent the formation of sand plugs in the delivery pipe.

30 Another difficulty experienced with both hand operated and fluid pressure operated track sanders is that water, being splashed upon the delivery pipe runs down same and in the cold weather freezes up the discharge end of the pipe and another object of this invention is to avoid this freezing of the delivery pipe by the provision of a novel nozzle which drains off any water or splashings which may run down the delivery pipe and 40 before such water reaches the discharge end of the delivery pipe.

Furthermore while it has been the practice to apply the delivery pipe of a track sander so that it will deliver the sand just in 45 advance of the car wheel and close to the meeting point of the wheel and rail, yet such delivery pipe does not follow the wheel when the car is rounding a curve and a further object of this invention is to so mount the delivery pipe of a track sander that the 50 relative position of the discharge end of the delivery pipe with that of a car wheel remains constant irrespective of the relative position of the wheel and car.

55 The above with further objects and advantages will be hereinafter more fully de-

scribed and particularly pointed out by the appended claims. For full comprehension, however, of my invention reference should be had to the accompanying drawings forming a part of this specification, in which similar reference characters indicate the same parts and wherein:

Figure 1 is a side elevation, partly in vertical section, of my improved track sanding device and illustrating its application to a car; Fig. 2 is a vertical section on line 2—2 Fig. 1; and Fig. 3 is an enlarged detail vertical section of the sand box and adjacent parts.

Referring now to these drawings, 2 indicates the sand box which is suitably mounted preferably vertically in the car and extends down below the floor 3 thereof, the bottom of the box being closed and the open top having a hinged cover 4 adapted to be clamped tightly over the top opening and being provided with a gasket 5 to form an air tight joint. A sand delivery pipe 6 extends from near the bottom of the sand box to the track while an air supply pipe 7 provided with valve 7^a leads into the box from a compressed air reservoir 8 and with the exception of the delivery pipe and when the cover 4 is clamped in place the sand box presents an air tight chamber so that when the air is admitted thereto it acts as a pressure accumulator to set up a back pressure which ejects the sand from the box to the delivery pipe.

In the preferred construction the inner open end 8^a of the sand delivery pipe is disposed at about the center of the sand box and such pipe extends outwardly through the side wall of the latter at substantially right angles to the vertical axis of the box, the air pipe extending inwardly as at 9 through the side wall, substantially parallel to and above the sand pipe and beyond the open end 8^a, such air pipe turning downwardly and continuing as at 10 in the vertical line of the box through the bottom of and to the exterior of the latter where it is closed by a removable cap or plug 11, such downwardly extending portion 10 having a 100 nozzle 12 set therein at a point opposite the opening 8^a. The nozzle extends toward but is spaced from the opening 8^a and the orifice of such nozzle is in the same plane as and concentric with opening.

The communicating port 13 between the nozzle and air pipe is, as usual, of lesser ca-

pacity than the air pipe so as to conserve the air supply and to avoid the blocking of such port by scale or other foreign particles which may be carried along the air pipe, the 5 continuation 10 is provided to form a trap into which such relatively heavy foreign particles drop instead of being directed to the nozzle, the vertical disposition of such trap assisting the gravitation of the particles which are removed by displacing the 10 plug 11.

In order to further avoid the possibility of scale entering and blocking the nozzle I provide a portion 14 which overhangs the 15 port 13 and forms a shelf over same which keeps the falling scale out from the port and this shelf is preferably formed by enlarging the portion 10 from a point above the nozzle, the bore of the air pipe being 20 eccentrically disposed relatively to the trap and the nozzle leading from the far side of the latter with respect to the air pipe.

When the valve 7^a controlling the passage through the air pipe is opened the air is 25 ejected from nozzle 12 and sand from the box is discharged through pipe 6 and upon the track, the friction set up in such pipe, if added to by a clogging of the sand, even although but a slight obstruction, causing 30 the air to bank up rearwardly through the pipe and so accumulate in the sand box until a sufficient back pressure is established to overcome the frictional resistance and the obstruction, it being obvious that this back 35 pressure will accumulate in the box owing to the fact that the inner end of the delivery pipe is open to said box. In this way the possibility is avoided of the sand so clogging the discharge pipe as to render it inoperative, even although the latter be disposed 40 horizontally for a considerable distance and this establishment of a back pressure is of particular advantage should the sand pipe become frozen up as then the air accumulates in the box until such time as the pressure is sufficient to blow the ice formation out of the pipe.

Upon closing valve 7^a and shutting off the air supply the established back pressure 50 in the box, if maintained, would continue to eject the sand and upon diminishing to an inadequate sand ejecting pressure would produce a sand residue in the discharge pipe sufficient to form a clogging plug but to 55 cure the advantage of the back pressure and avoid the disadvantage just described I provide means for relieving the back pressure simultaneously with the shutting off of the air supply and particularly for relieving 60 such back pressure at a point adjacent the opening 8^a of the sand pipe so that the latter is instantly relieved of pressure the instant the air supply from pipe 7 ceases.

The means for relieving the back pressure 65 consists of a relief passage extending from

the sand box and preferably from a point adjacent opening 8^a to the exterior of the box and the atmosphere, a valve being set in the relief passage and adapted to be closed when valve 7^a is opened and, vice versa. 70 The relieving means shown in the drawings consists of an open-ended pipe 15 leading from the box to the atmosphere and having a valve 16 set therein, upon the opening of which the back pressure exhausts to the atmosphere. To provide for the instant relief of the pressure about the discharge pipe opening, which relief would otherwise be retarded by the sand, I provide an open-ended pipe 18 which extends from a point adjacent 75 to and at one side of the opening 8^a to a point adjacent the inner end of pipe 15 and in the preferred construction the upper end of pipe 18 and inner end of pipe 15 are disposed above the highest line of sand repose, 80 said inner end being upturned as at 15^a to prevent sand reaching and collecting upon the seat of valve 16.

As above stated and to secure the desired result the valves 7^a and 16 are operated 90 simultaneously and in order to conveniently operate same I utilize a double valve casing divided by partition 19 having at one side the valve 7^a and communicating with the pipe 7 at such side and having the valve 16 95 and communicating with pipe 15 at the other side, the valve stems projecting through the casing and being operated to alternately open and close their respective valves simultaneously by a double bell-crank 100 lever 20 connected by links 21 to a foot lever 22.

The inner portion 6^a of the sand delivery pipe 6 or that portion adjacent the box extends outwardly in a horizontal line from the sand box, then laterally at 23 for a short distance and continues horizontally, this offset portion 23 preferably inclining upwardly and outwardly and constituting a trap for preventing the passage by gravity 110 of sand through the delivery pipe. The air pressure is necessary to force the sand up through the offset portion and upon the simultaneous shutting off of the air and relief of back pressure the discharge of sand 115 ceases, the upper end of the offset portion being upwardly enlarged at 24 and having a shelf 25 at the bottom thereof forming a pocket wherein a quantity of sand accumulates during the discharge and protects the 120 bend of the pipe from wear. The inner portion of the discharge pipe is extended slightly beyond the bottom of the offset 23 to also form a pocket for the reception of a quantity of sand and consequent protection 125 of the pipe at the bend, a removable plug 26 being inserted in the end of the portion 6^a to permit of the latter being cleaned.

The sand discharge pipe extends beneath the car flooring to the wheel truck 27 swiveled 130

to the car and the pipe is attached at 28 to said truck, the discharge end of the pipe extending downwardly and being branched transversely of the car at 29 to provide discharge openings just in front of the wheels and close to the rails and the meeting points of the latter and the wheels, it being preferred to locate the discharge ends of the pipe just in front of the second pair of wheels from the forward end of the car and so enable the first wheels to clean the rails and prepare the latter for effective sanding.

The branched discharge end of the sand pipe is rigidly braced and suspended from the trunk by a hanger 30 so as to constantly maintain the outlet ends of the pipe in position in front of the wheels and the portion of such pipe disposed between the wheel truck and sand box is upheld by flexible hangers 31 and provided with a movable connection with the truck consisting preferably of flexible lengths 31 and 32 set in the pipe adjacent the truck and box respectively, this movable connection permitting the discharge end of the pipe to move with the truck and accommodating the consequent relative movement of such discharge end with respect to the main portion of the pipe when the car negotiates a curve. In this way the relative position of the wheels and discharge end of the sand pipe is constantly maintained irrespective of the relative position of the wheels and car.

Each of the discharge ends of the sand pipe is provided with a nozzle 33, such nozzle having parallel interior surfaces and being formed with transverse end flanges 34 which taper downwardly to a point 35, the discharge opening of the nozzle also converging at the lower side. The flanges 34 are disposed transversely to the sand pipe and form exterior ridges or baffles thereon so that any water that may run down the exterior of the pipe is caught by the baffles and drips from the points 35, being thus prevented from reaching the discharge opening and in order to avoid the clogging of the latter should moisture, drawn therein by capillary action, tend to cake any sand that may be therein, I have enlarged at 36 the bore of the discharge ends of the said pipe.

What I claim is:

1. In a track sander, a pressure retaining sand box, a sand ejecting device, means for supplying air pressure to the sand ejecting device and building up a back pressure in the box and means for removing the back pressure at substantially the same instant that the air pressure is shut off from the sand ejecting device.

2. In a track sander, a pressure retaining sand box, a sand ejecting device located in the lower portion of said box, a sand delivery pipe connected to said ejecting device, means for applying air pressure to the said

ejecting device and building up a back pressure in the box, means for quickly removing the back pressure from the base of sand box and near the entrance of the sand delivery pipe, and instantly stopping the discharge of the accumulated back pressure through the sand delivery pipe, when air pressure is shut off from the ejecting device.

3. In a track sander, a box containing sand and having a sand delivery pipe adjacent the bottom, means for tightly sealing all openings in said box except sand delivery pipe, means for supplying air pressure and sand to said sand delivery pipe and building up a back pressure in the box, and means for instantly removing the back pressure at the entrance of said sand delivery pipe when the supply of air pressure is shut off from said sand delivery pipe.

4. In a track sander, a sand box having a sand discharge opening, a pipe for supplying air to the sand box to eject the sand, means for opening and closing the passage through the pipe, an air conduit leading from the sand box to the atmosphere and means for opening and closing the passage through such conduit alternately with the opening and closing of the pipe.

5. In a track sander, a sand box having a sand discharge opening, a pipe for supplying air to the sand box to eject the sand, means for opening and closing the passage through the pipe, an air conduit leading from the sand box to the atmosphere, means for opening and closing the passage through such conduit alternately with the opening and closing of the pipe and a device for simultaneously operating the controlling means of the pipe and conduit.

6. In a track sander, a sand box having an air tight cover and a sand discharge opening, a pipe for supplying air to the sand box, such sand box being air-tight with the exception of the discharge opening and adapted to accumulate a back pressure therein, an air conduit leading from the sand box to the atmosphere, means normally closing such conduit and adapted to open same to relieve the back pressure in the box.

7. In a track sander, a sand box having a sand receiving opening and a sand discharge opening, an air tight cover for the receiving opening, a pipe for supplying air to the box to eject the sand and a conduit different from the sand receiving opening, discharge opening and air pipe, such conduit leading from the interior of the box to the atmosphere.

8. In a track sander, a sand box having a sand receiving opening and a sand discharge opening, an air-tight cover for the receiving opening, a pipe for supplying air to the box to eject the sand, a valve in the air supply pipe, a conduit different from the sand receiving opening, discharge opening

and air pipe, such conduit leading from the interior of the box to the atmosphere, a valve in said conduit and means for simultaneously and alternately opening and closing said 5 valves.

9. In a track sander, a sand box having a sand discharge opening, a pipe for supplying air to the box to eject the sand, a pipe located within the box and extending from 10 a point near the opening of the air pipe into the latter to a point above the line of sand repose, a relief pipe communicating at one end with the atmosphere and at the opposite end with the interior of the box at a 15 point above the line of sand repose, and means for controlling the passage through the air pipe and relief pipe.

10. In a track sander, a sand box having a sand discharge opening, a pipe for supplying air to the box to eject the sand, a valve 20 controlling the passage through the air pipe, an open-ended pipe located within the box and extending from a point near the opening of the air pipe into the latter to a point 25 above the line of sand repose, a relief pipe communicating at one end with the atmosphere and at the opposite end with the interior of the box at a point above the line of sand repose, a valve controlling the passage 30 through the relief pipe and a double bell-crank lever adapted to simultaneously and alternately open and close said valves.

11. In a track sander, a sand box, a sand discharge pipe extending outwardly 35 from a point inside the box, a pipe for supplying air to the box to eject the sand, said pipe extending inwardly substantially parallel with the sand pipe, to a point beyond the inner end of same where it extends downwardly through the wall of the sand box, a 40 removable plug upon the end of the downwardly extending portion of the air pipe and a nozzle set in such downwardly extending portion at a point opposite the inner opening of the sand pipe, the orifice of 45 such nozzle being in the same plane as, spaced a short distance from and concentric with said inner opening of the sand pipe.

12. In a track sander, a sand box, a sand 50 discharge pipe extending outwardly from a point inside the box, a pipe for supplying air

to the box to eject the sand, said air pipe extending horizontally inwardly to a point beyond the inner end of the sand pipe where it continues downwardly through the bottom of the box, a removable plug at the lower end of the downwardly extending portion, a nozzle set in the downwardly extending portion of the pipe and a shelf in the air pipe and disposed just above the entrance to the nozzle. 55

13. In a track sander, a vertical sand box, a sand discharge pipe extending horizontally outwardly from a point inside the box, a pipe for supplying air to the box to eject 60 the sand, said air pipe extending horizontally inwardly to a point beyond the inner end of the sand pipe where it continues downwardly across the inner opening of the sand pipe and through the bottom of the 65 box, being enlarged at a point opposite said inner opening, a removable plug at the lower end of the downwardly extending portion and a nozzle set in the enlarged portion of the air pipe, the entrance of the nozzle being 70 overhung by the top of the enlarged portion. 75

14. The combination with a car having a wheel truck swiveled thereto, of a track sander consisting of a sand box, a rigid sand delivery pipe, flexible hangers suspending the rigid 80 pipe from the car, a sand discharge pipe portion carried rigidly upon the truck, a flexible pipe length between the sand box and one end of the rigid pipe and a second flexible length between the opposite end of 85 the pipe and the discharge pipe portion carried by the truck.

15. In a track sander, a sand box, a sand delivery pipe extending from the sand box and being enlarged near the discharge end, 90 and a nozzle at the discharge end of the sand pipe, said nozzle having exterior flanges which are disposed transversely to the nozzle and taper downwardly to a point. 95

In testimony whereof, I have signed my name to this specification, in the presence of two subscribing witnesses.

OTTO WILLIAM MEISSNER.
